Frank Caldwell,

By John Elias Jones,

ATTORNEY.

UNITED STATES PATENT OFFICE.

FRANK CALDWELL, OF CINCINNATI, OHIO.

SPRAY-DISCHARGE EQUALIZER.

1,224,852.

Specification of Letters Patent.

Patented May 1, 1917.

Application filed August 23, 1915. Serial No. 46,864.

To all whom it may concern:

Be it known that I, FRANK CALDWELL, a citizen of the United States of America, and a resident of Cincinnati, in the county of Hamilton and State of Ohio, have invented a certain new and useful Improvement in Spray-Discharge Equalizers, of which the following is a specification.

This invention relates to fuel-gas equalizers or receptacles in which the gases are intended to be uniformly mixed and discharged into the power-cylinders of automobile or like engines using gas, gasolene or kerosene or other combustible liquid fuels.

The object of the invention herein and the details of its structure will be fully herein-after referred to in connection with the description of the accompanying sheet of drawings, in which, Figure 1 is a longitudinal section of the equalizing-receptacle, shown surmounting an inlet, secondary mixing-coil, which latter is in elevation and also surmounts the ordinary carbureter or primary mixing-chamber, suitable gas and air intakes being shown in connection with said carbureter; and Fig. 2, a broken, sectional elevation taken on the dotted-line *a*, *a*, of Fig. 1.

1 indicates the ordinary carbureter or primary mixing-chamber, of any suitable construction and having a gas or oil intake 2 and an air-intake 3.

4 indicates a coil of pipe of any desired number and pitch of convolutions to suit the capacity of the device, taken as a whole herein, that includes, also, the said primary mixing-chamber as well as the final equalizer. This coil has a horizontal flange 5 at its lower end for coupling with the upper exit-formation 6 on the carbureter 1 and it also has a similar vertical flange 7 at its upper end that is connected to the boss or inlet-formation 8 that opens sidewise in the pendant, centrally-aligned chamber 9, extending from the tapered bottom 10 of the equalizing-receptacle 11.

The equalizing-receptacle 11 has an elongated but narrow chamber that has an upper, horizontal capping-wall 12 from which is extended downwardly a series of vertical partitions or webs 13 that form baffle-plates in the upper portion of the equalizing-chamber. These webs 13 are preferably made integral with the side and top walls of the equalizing-chamber and extend transversely

and in open array across the width of said chamber, suitable outlet-openings 14 being provided in the "off" side-wall of the chamber 11 for the discharge of the properly mixed gases into the several engine-cylinders. The outlets 14 are located at equal distances apart in relation to the said webs 13 so that the finally agitated and admixed gases are equally liberated from the main part of the chamber 11, below the lower edges of said webs, into said engine-cylinders and whereby each engine-cylinder has a uniform supply of the now homogeneous mixture and thus preventing any unequal distribution or quality of said vapors from the carbureter into said cylinders in use. A suitable, short nozzle-formation or shoulder 15 is provided on the outer face of the said "off" side of the equalizing-chamber 11 concentric to each outlet 14, whereby gasketed-connection is made between said outlets and the several engine-cylinders.

The "near" side of the equalizing-chamber 11 is rounded at its upper corner 16, as shown in Fig. 2, to facilitate the outward passage of the said homogeneous mixture leading from the said equalizing-chamber through the outlet-orifices 14 and thus obviates any "dead" pockets or corners in the device.

In the operation of the device herein shown, the gas or oil and the air are independently liberated into the carbureter or primary mixing-chamber under suitable valve-control as customary. The admixture from said carbureter then ascends in the coil 4 where it is again thoroughly mixed in its passage through the coil, the circuitous passage through the coil assuring such thorough mixing while in transit from the primary - mixer or carbureter. The vapor then further ascends or passes from the coil 4 into the chamber or receptacle 11 where it expands and becomes thoroughly agitated or what may be termed "churned" into a volume of homogeneous vapor that arises or passes onward into the separate or partitioned chambers provided by the webs 13, the latter splitting such volume of homogeneous vapor, that has now become a fixed gas, into practically equal lesser volumes or charges that thence pass laterally, under equal distribution, through the orifices 14 into the successive engine-cylinders. The webs 13 form baffle-plates that retard and

split the entire volume or charge of vapor arising from the coil 4 so that said main volume of vapor cannot find exit through but certain ones of the outlets 14 that might 5 otherwise form a more direct passage, it being important that all outlets 14 shall be equally provided with power-vapor, thoroughly mixed and equally distributed to all the cylinders alike. Thus all the outlets or 10 escapes 14 have a uniform quality of gas-discharge and all the engine-cylinders are under an equal pressure for work. Thus no cylinder has any advantage over the other in its supply of power vapor or gas that is 15 not richer in one cylinder than it is in any of the others.

I claim:

1. A manifold comprising a shell having a lower intake and upwardly projecting 20 parallel side walls connected at their upper ends, and one of which has a horizontal series of laterally opening outlets adjacent its

said upper end, a top wall connecting the said upper ends of said side walls, the other side wall having its upper end rounded adjacent the top wall and opposite the said outlets, and transverse partition plates connecting said side walls and arranged between the several outlets of the series, each of said partition plates depending from the top wall to a point below the lower edges of 25 said outlets.

2. A manifold comprising a shell having a horizontal series of outlet openings adjacent its upper end, and a series of partition 30 plates extending transversely therein and across the same between the several outlet openings, each of said plates depending from the upper end of the shell to a point below the lower edges of the said outlets. 35

FRANK CALDWELL.
